ABSTRACT OF THE DISCLOSURE

A vapor deposition material support for securement to and between the spiral turns of a heater filament, the support consisting of a planar tungsten shelf held in place by a tungsten wire clip. The shelf is of the same shape as the spiral filament cross-section, is of larger area than that of the open cross-section within the spiral at the point of securement, and of smaller area than that of the overall cross-section of the spiral filament to thereby form a walled well with a spiral loop of the filament. The clip is formed of a single piece of tungsten wire bent to provide three upwardly inturned hooks spaced substantially one hundred twenty degrees apart about a perimeter substantially the same as that of the overall cross-section of the spiral filament at the point of securement. Two of the clip hooks are end hooks formed by the opposite ends of the tungsten wire and are joined by legs to an intermediate third hook which is formed up out of the center of the wire by reversely folding the wire back next to itself, the two end hooks being otherwise unconnected to one another. The bight of each of the hooks is large enough to accommodate the shelf thickness together with the diameter of the wire which forms the turns of the heater filament. The shelf and the filament cross-section illustrated in the drawings are both circular, and the illustrated clip is shown with hooks which lie substantially at the vertices of an equilateral triangle.

This invention relates generally to the art of thermal evaporation which is used in industry to coat various materials such as glass, aluminum and steel, and more particularly to the coating of glass, as for example the coating of prisms, lenses and mirrors.

A widely used coating material for these applications is pelletized magnesium fluoride which is set upon a tungsten shelf inserted between successive spiral turns of a helically coiled tungsten wire filament, the helical axis being vertically oriented. A vacuum is then drawn within the evaporation chamber and the filaments are electrically energized to melt and evaporate the magnesium fluoride for deposition coating of the glass. This process is very chancey, for as often happens the unsecured shelf slips out from between the filament spirals which shift due to thermal expansion and contraction, carrying with it the melted magnesium fluoride. When this occurs, the molten magnesium fluoride falls to the floor of the vacuum chamber and spatters itself non-uniformly over the entire charge of glass. This requires that, the process be shut down, the chamber be opened and the glass be removed and re-processed for coating. The probability of such an occurrence is of course multiplied by the number of filaments utilized in a given chamber, with some chambers having twenty-five or more such filaments.

Many of these articles are worth substantial sums of money and the financial loss to a manufacturer can be staggering. By way of illustration, in coating optics and prisms, a typical coating cycle for thirty prisms would be approximately 16 hours. It has been established that a processor may stand a loss of approximately \$600.00 per hour when a shelf falls out of a filament, and as has been pointed out, a shelf is likely to fall at any time dur-

2

ing the operation due to vibration or thermally induced movement.

Tungsten shelves and filaments are used because they are substantially inert and do not contaminate the processed parts. However, tungsten is not only hard but is also brittle so that the shelves cannot be bent to provide a securing means. This has led to the use of tantalum for shelves since this latter material is relatively soft and can be deformed to secure the shelf to a filament. However, not only is tantalum substantially more expensive than tungsten, but much more important is the fact that tantalum outgases when heated and produces a highly undesirable yellow cast or tint in the coating, resulting in an inferior product. Accordingly, it is a primary object of my invention to provide a novel clip for quickly and easily firmly securing a metal shelf to and between the spiral turns of a vacuum chamber filament to form a stable support for vaporizable material placed thereon.

Another object of my invention is to provide a novel clip as aforesaid which is substantially inert so as to avoid contamination of the vaporizable material.

Still another object of my invention is to provide a novel clip as aforesaid which is simple and inexpensive to make.

25 A further object of my invention is to provide a novel assembly of the clip as aforesaid and a tungsten shelf which together form a walled well with a spiral turn of a heating filament to contain the thermally fluidized vaporizable material employed in vapor deposition.

The foregoing and other objects of my invention will appear more fully hereinafter from a reading of the following specification in conjunction with an examination of the appended drawing, wherein:

35 FIGURE 1 is a side elevational view of the clip and shelf according to the invention secured in operative position to a spiral coil of a helically wound heater filament;

FIGURE 2 is an enlarged perspective view of the clip and shelf according to the invention shown affixed to the heater filament, parts of which have been sectioned away for better visibility;

35 FIGURE 3 is an enlarged plan view of the clip and shelf according to the invention secured to the filament of FIGURE 1 as would be shown when viewed along the line 3—3 of FIGURE 1;

45 FIGURE 4 is an enlarged fragmentary side elevation of the clip and shelf according to the invention being mechanically installed to the helical filament;

FIGURE 5 is a vertical sectional view through the installed clip and shelf as would be seen when viewed along the line 5—5 of FIGURE 3;

55 FIGURE 6 is a vertical sectional view similar to that of FIGURE 5 but taken at substantially a right angle thereto and as would be seen when viewed along the line 6—6 of FIGURE 5;

FIGURE 7 is a fragmentary view showing the remaining detail of the end hook engagement as would be seen when viewed along the line 7—7 of FIGURE 3;

60 FIGURE 8 is a plan view of the metal shelf used in the combination;

FIGURE 9 is a top plan view of the clip according to the invention;

FIGURE 10 is a front elevation of the clip seen in plan view in FIGURE 9, as would be seen when viewed along the line 10—10 of FIGURE 9; and

FIGURE 11 is a side elevational view of the clip as would be seen when viewed along the line 11—11 of FIGURE 10.

In the several figures, like elements are denoted by like reference characters.

Referring now to the drawing, there is seen a clip designated generally as 20 holding a circular shelf 21 to one

spiral loop of a filamentary heater 22, the heater being formed usually of tungsten wire in the form of a helical coil with a vertically oriented axis and opposite ends 23 connectable to a source of electrical energization. As best seen from FIGURES 2 and 8, the shelf 21 is circular, and as best seen from FIGURES 1, 5 and 6, the diameter of the circular shelf is greater than the inside diameter of the spiral loop 24 of the heater 22 to which the shelf is secured by the clip 20 while also being less than the outside diameter of the same spiral loop.

As best seen from the showing of FIGURES 1 and 2 this results in the formation of a well of which the bottom is formed by the shelf 21 while the side walls are formed by the spiral loop 24 to which the shelf is clipped. As is best seen from FIGURES 1, 5 and 6, the shelf 21 is disposed with its plane not precisely horizontally oriented, but rather inclined at a slight angle, the inclination of the shelf is such that the portion of the spiral loop 24 designated as 24a in FIGURE 2 spirals upward away from and out of contact with the shelf 21 on the high side of the inclined shelf 21. Consequently, as a pellet of the fluidizable coating material passes from a solid to a molten state, any tendency of the molten material to flow across the surface of the shelf 21 is in such direction due to gravity as to move it away from the perimetrical unconfined high point edge of the shelf and toward the completely walled regions of the shelf which are gravitically lower. This of course eliminates any possibility of escape of the molten coating material from the confines of the filament walled shelf so long as the shelf 21 is properly held in position to the filament 22 by the clip 20.

The clip 20 is best seen in the plan view and elevational showings of FIGURES 9, 10 and 11 where it is observed that the clip 20 is formed of a single piece of wire-like material having the opposite ends 25 each formed into an upwardly inturned hook 26, the lower ends of which turn horizontally in plane into a pair of curved legs 27 which curve inward toward one another and turn into substantial parallelism before turning upward and inward to merge with one another and form the intermediate hook 28.

The end hooks 26 and intermediate hook 28 lie substantially on the vertices of an equilateral triangle in the form of the clip as illustrated, although this is not mandatory. The optimum configuration for the clip is one in which the shelf 21, of whatever geometric shape, is held captive within the clip so that it cannot slip laterally outward between any two of the adjacent hooks. Similarly, while the shelf 21 is shown as being of circular form, this is so because the cross-section of the helically wound filamentary heater 22 is circular. The requirement for the shelf 21 is that it shall be of sufficient area and proper shape to close the cross-section of the heater to which it is to be secured, regardless of the shape of the heater cross-section. Similarly, the clip configuration is required to securely hold the shelf, of whatever shape, to the filamentary heater, again of whatever shape, and to be of such configuration as to permit quick and easy positive securing of the shelf to the heater.

The straight line distance between the end hooks 26 of the clip 20 and designated in FIGURE 10 by the dimension B must be less than the outside diameter of the spiral loop 24 of the heater 22 in the illustrated configuration, and the distance from this base line B to the inside of the intermediate hook 28 designated in FIGURE 3 as A must be greater than the radius of the spiral loop 24. With the clip 20 made of a springy or resilient material, this results in an installed condition of the clip where the end hooks 26 are pressing inward against the outer sides of the spiral loop 24 at points on the periphery of the latter which pull the intermediate hook 28 inward against the spiral. This is best seen from the showings

of FIGURES 3 and 4 to which reference should now be made.

As shown in solid line in FIGURE 4, and in phantom outline in FIGURE 3, the clip 20 with the shelf 21 disposed therewithin is positioned so that the end hooks 26 bear against the outside periphery of the spiral loop 24 with the shelf 21 just underlying the spiral loop 24. The intermediate hook 28 is then pressed laterally toward the spiral loop 24 as indicated by the arrow 29. The clip end hooks 26 shift laterally outward and follow around the periphery of the spiral loop 24 as the intermediate hook 28 moves inward toward and finally against the proximate edge of the spiral loop, the end hooks 26 overriding the diameter of the spiral loop and moving inward again toward one another to their final position. The shelf 21 is then held firmly as illustrated.

While the hook 20 and shelf 21 are preferably made of tungsten metal, all applications may not require this, and other suitable materials may be used as long as the previously described design criteria are taken into account.

Having now described my invention in conjunction with a particularly illustrated embodiment thereof, it will be appreciated that variations and modifications of my invention may now occur from time to time to those persons normally skilled in the art without departing from the essential scope or spirit of my invention, and accordingly it is intended to claim the same broadly as well as specifically as indicated by the appended claims.

What is claimed to be new and useful is:

1. A vapor deposition material support comprising in combination,

(a) a heater characterized by the inclusion of a filamentary loop,

(b) a shelf, and

(c) shelf securing means operative to secure said shelf to the said heater filamentary loop,

said shelf extending transversely to the said filamentary loop and in contact with a substantial part of said filamentary loop to thereby form at least a partly walled well with said filamentary loop operative to retain molten vapor deposition material on said shelf within the confines of said partly walled well.

2. A vapor deposition material support as defined in claim 1 wherein said shelf is made of metal and said shelf securing means holds said shelf in good thermal contact with said heater.

3. A vapor deposition material support as defined in claim 1 wherein said shelf securing means comprises a clip having a plurality of hooks which each extend from a point underlying said shelf upward about the shelf edge and a portion of said filamentary loop.

4. A vapor deposition material support as defined in claim 1 wherein said shelf securing means comprises a clip formed of a single piece of metal wire bent to provide three upwardly inturned hooks spaced apart about a perimeter substantially the same as that of the overall cross-section of said filamentary loop at the point of shelf securing, two of said hooks being end hooks formed by the opposite ends of said wire and joined by legs to an intermediate hook formed from the wire at substantially the center of said wire.

5. A vapor deposition material support as defined in claim 1 wherein said shelf securing means comprises a clip formed of a single piece of metal wire bent to provide three upwardly inturned hooks spaced apart about a perimeter substantially the same as that of the overall cross-section of said filamentary loop at the point of shelf securing, two of said hooks being end hooks formed by the opposite ends of said wire and joined by legs to an intermediate hook formed from the wire at substantially the center of said wire, said end hooks being unconnected to one another except by said legs and being resiliently shiftable with respect to one another, whereby said end hooks may accommodate themselves to engage a plurality of points about the periphery of said filamentary loop.

6. A vapor deposition material support as defined in claim 1 wherein said shelf is made of metal and said shelf securing means holds said shelf in good thermal contact with said heater, said shelf securing means comprising a clip formed of a single piece of metal wire bent to provide three upwardly inturned hooks spaced apart about a perimeter substantially the same as that of the overall cross-section of said filamentary loop at the point of shelf securement, two of said hooks being end hooks formed by the opposite ends of said wire and joined by legs to an intermediate hook formed from the wire at substantially the center of said wire, said end hooks being unconnected to one another except by said legs and being resiliently shiftable with respect to one another, whereby said end hooks may accommodate themselves to engage a plurality of points about the periphery of said filamentary loop.

7. A vapor deposition material support as defined in claim 3 wherein said clip hooks are spaced substantially equally about the periphery of a circle, and wherein said shelf is substantially in the form of a circular disc of somewhat smaller diameter than that of the circle about

5

10

15

20

which said clip hooks are spaced but of larger diameter than the distance between any two of said clip hooks.

8. A vapor deposition material support as defined in claim 6 wherein said shelf and clip are made of tungsten, wherein said clip hooks are spaced substantially equally about the periphery of a circle, and wherein said shelf is substantially in the form of a circular disc of somewhat smaller diameter than that of the circle about which said clip hooks are spaced but of larger diameter than the distance between any two of said clip hooks.
